UNITED STATES PATENT OFFICE.

SAMUEL T. WELLMAN AND GEORGE W. GOETZ, OF CLEVELAND, OHIO.

REVOLVING PUDDLING-FURNACE.

SPECIFICATION forming part of Letters Patent No. 358,763, dated March 1, 1887.

Application filed January 16, 1886. Serial No. 183,718. (No model.)

To all whom it may concern:

Be it known that we, SAMUEL T. WELLMAN and GEORGE W. GOETZ, of Cleveland, in the county of Cuyahoga and State of Ohio, have invented certain new and useful Improvements in Revolving Puddling-Furnaces; and we do hereby declare the following to be a full, clear, and exact description of the invention, such as will enable others skilled in the art to which

10 it pertains to make and use the same.

Our invention relates to improvements in revolving puddling furnaces in which the shell or casing of the furnace is made to correspond with the desired internal configuration of the 15 lining, preferably polygonal—for instance, a pentagon—to the end that, with the lining of such internal form in cross-section as may be considered best adapted to revolve and properly work and shape the mass being treated in 20 the furnace, the said lining may be made of uniform thickness, and thereby rendered more durable than linings of unequal thickness, as heretofore used in this class of furnaces.

Heretofore the shells of revolving puddling- 25 furnaces have been round in cross-section and provided with a lining, usually of iron ore. It is not practicable to have the inner face of the lining approximate a round smooth surface, for the reason that some projections, depressions, 30 or angularities of form are necessary to rotate the mass being treated by carrying the mass up along the ascending side of the furnace, so that the same may roll and tumble back by gravity, such rolling and tumbling being es- 35 sential to properly work and shape the mass. When the lining is approximately round and smooth on its inner face, the semi-molten mass slides on the lining and is not elevated enough to be rotated, and, instead of being properly 40 worked and shaped into a ball or suitable round form in cross-section, the mass is spread out in broad unwieldy proportions, so that it cannot be properly handled in working or removed from the furnace.

45 With a round shell it is evident that any projections, depressions, or out-of-round shape given to the face of the lining must result from the lining being made of unequal thickness. The shell of the furnace is kept cool, sometimes 50 by means of water-chambers connected therewith and sometimes by means of water sprin-

kled on the shell, by reason of which the lining next adjacent to the shell is kept at a moderate temperature. The thicker portions of the lining become overheated and are soon wasted 55 away, so that, usually after a run of perhaps four or five hours, or less, the out-of-round features will have disappeared, and consequently the furnace will have ceased to perform its functions of working and shaping the mass of 60 material being puddled, necessitating a stoppage of perhaps two hours, (more or less,) to renew portions of the lining to give it its out-of-round character. Of course such frequent stoppages greatly increase the cost of puddling 65 in this class of furnaces. In view of these difficulties we have devised the following, to wit: We first decide what form in cross-section for the face of the lining will be likely to give the best results, and then build a casing to corre- 70 spond, so that the lining, when made of uniform thickness, will at the same time be of the desired form inside. With such construction there are no thick places to become overheated and rapidly wasted away, resulting in a radi- 75 cal change of the form, always tending toward a round shape corresponding with the shell; but, on the contrary, the lining, being of uniform thickness, remains at an even tempera- 80 ture, so that the wear and tear is about evenly distributed, and the tendency is to retain the desired original form of lining corresponding with the shell.

With our improved construction the lining is much more durable than in furnaces as heretofore constructed. We find that a polygonal 85 form in cross-section is well adapted to the purpose, and we prefer a pentagon, and have so illustrated our invention in the accompany- 90 ing drawings; but we do not wish to be understood as limiting ourselves in anywise to this particular form.

Figure 1 is an elevation, in longitudinal section, of a furnace embodying our invention. Fig. 2 is a side elevation in transverse section 95 through the center of the furnace.

A represents the shell of the revolving fur- 100 nace, and a the lining to the same. As shown in Fig. 2, the form of the shell in cross-section is a pentagon, and the lining is intended to be of uniform thickness, so that the inside of the lining is of corresponding shape with the shell.

This form is found to be well adapted to roll and tumble the mass being treated, so as to properly work the same and form it into suitable shape to be handled and removed from the furnace. The annular tracks B and gear C may be attached in any suitable manner to the shell, one form of attachment being shown in Fig. 2, where flanges b are secured to the angles of the shell, and in turn support, respectively, the tracks and gear. The tracks B turn on the wheels D, arranged in the usual manner, and the gear C is engaged by a gear, C', connected with the driving-engine e, that may be of the ordinary construction.

15 The fire-box E and the movable smoke-box F, the latter connecting the revolving furnace with the chimney, are substantially as heretofore used.

We are aware that a cylindrical casing having a lining of unequal thickness is not new. We are also aware that it is old in revolving roasters to construct the casing of a series of short curved sections secured together, and provide same with a lining substantially parallel with the inner face of the casing. We are also aware that a polygonal furnace constructed

of iron lined with fire-clay and shaped in the form of a pyramid or cone is not new, and hence we make no claim to such constructions.

In our device the casing and lining are made up of a series of plane surfaces, which are better adapted to roll and tumble the mass being treated than the curved sections above referred to, and are more durable than the linings of unequal thickness.

35

What we claim is—

In a revolving puddling-furnace, the combination, with a shell having reduced ends, as shown, the body of said shell being made polygonal and preferably pentagonal in cross-section, of a lining arranged inside of the shell, said lining being substantially of uniform thickness, so as to conform on its inner face to the shape of the shell, substantially as set forth.

40

In testimony whereof we sign this specification, in the presence of two witnesses, this 9th day of January, 1886.
